CLAIM

The ornamental design for a laptop camera cover, as shown and described.

DESCRIPTION

FIG. 1 is a rear isometric view of a laptop camera cover showing my new design;

FIG. 2 is a front isometric view thereof;

FIG. 3 is a top plan view thereof;

FIG. 4 is a rear elevation view thereof;

FIG. 5 is a bottom plan view thereof;

FIG. 6 is a side elevation view thereof;

FIG. 7 is a front elevation view thereof; and,

FIG. 8 is an isometric view thereof in context of use.

The broken lines shown in FIG. 8 depict environmental subject matter and form no part of the claimed design.
